HS ATTORNEY.

UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

LOCATING DEVICE FOR DRILL MOUNTINGS

Application filed July 12, 1930. Serial No. 467,395.

This invention relates to locating devices, but more particularly to locating devices adapted to locate a rock drill mounting with respect to the rock intended to be drilled.

5 One well known method of quarrying rock comprises drilling rows of suitably spaced drill holes and broaching the intervening walls of rock between the drill holes to form continuous cuts through the rock. The working implements employed in these operations, namely the drilling steel and the broaching tool, may be actuated by the same rock drill which is preferably supported on a mounting adapted to be drawn across the surface 10 of the rock. The mounting is usually drawn twice along the intended line of cut in the rock to complete the cut, one trip being required for the drilling of the spaced drill holes and the other for the broaching operations.

The efficiency of this method of drilling depends to a considerable extent upon the proper spacing of the drill holes since, when the drill holes are properly spaced, the required number of operations to form the cut of a desired length will be minimized. It is an object of the present invention to assure the accurate spacing of the drill holes.

Another object of the invention is to hold 30 the drill mounting immovable during the drilling and broaching operations.

Other objects will be in part obvious and in part pointed out hereinafter.

In the drawings illustrating the invention 35 and in which similar reference characters refer to similar parts,

Figure 1 is a side elevation of a locating device for rock drill mountings constructed in accordance with the practice of the invention and showing it applied to a rock drill vehicle mounting,

Figure 2 is a transverse view taken on the line 2—2 of Figure 1 looking in the direction indicated by the arrows, and

45 Figure 3 is a view of a detail.

Referring to the drawings, A designates the platform of a vehicle to which are secured axles B and C carrying pairs of wheels D (only one of each pair being shown). The vehicle may be of a type adapted to be moved

along a track laid on a quarry floor and accordingly the wheels D are shown provided with the usual flanges E for cooperation with rails F. Ties G may be interposed between the rails F and the rock floor H of the quarry. Secured to the platform A, preferably at one side thereof, is a vertical frame J which may be braced by one or more diagonal struts K. The frame J provides a guideway for a saddle L on which is secured a rock drill O. A drill steel P is shown extending into the forward end of the rock drill O and carries a cutting bit (not shown) for drilling holes Q into the rock H. Usually the weight of the rock drill O and its associated parts is sufficient to create the necessary pressure on the cutting bit to drill the holes Q, and preferably means, such as a power hoist (not shown), is operatively connected to the saddle L or the rock drill O in any convenient manner to quickly elevate the rock drill upon the completion of a hole.

To facilitate the starting of drill holes which is normally difficult due to the tendency of the cutting bit to travel over a wide area on the surface of the rock, a drill steel centralizer of any well known design may be employed. In the drawings, I show a centralizer comprising a pair of movable arms R pivotally secured in brackets S which may be bolted or otherwise secured to the opposite sides of the frame J. The free ends of the arms R may be formed with registering grooves to receive the drill steel P and may be secured together by a clip T.

In accordance with the present invention, means are provided for accurately spacing the drill holes Q with respect to each other. The means includes a pair of stop plates U and V seated on the rail F in position to arrest movement of the vehicle in either direction on the track. Preferably the stop plates U and V are disposed on opposite sides of one of the wheels D and the adjacent ends of the plates may be provided with curved bearing surfaces W conforming to the contour of the bearing surfaces of the wheel D for which they form abutments.

The stop plates U and V are preferably connected by flexible means, such as a chain

X, which is shown interlocked at its ends to eye bolts Y adapted to be received in the stop plates U and V. If desired, the bolts Y may be inserted through laterally extending ears Z on the plates U and V and nuts b may be threaded on the ends of the bolts to secure the bolts in the ears. I contemplate operating the rock drill O with the vehicle in its limiting positions as determined by the maximum spacing of the stop plates U and V which is afforded by the chain X and the associated connecting means to thereby effect the proper spacing of the drill holes. By adjusting the nuts b the maximum spacing of the plates U and V and consequently the spacing of the drill holes Q may be varied.

In order to maintain the stop plates U and V on the rail F longitudinally extending slots c may be formed in the under side of each plate to receive the rail. Set screws d are preferably employed to fixedly secure the stop plates U and V to the rail F and are shown extending transversely of the plates into the slots c to engage one side of the rail F. The sides of the stop plates U and V which lie at the same side of the rail F as the flange E of the wheel D preferably lie flush with the rail for a portion of the length of each plate so that the surfaces W may contact with the bearing surfaces of the wheel rather than with the flange E.

In operation, the position of the vehicle for drilling the first hole of a series of drill holes may be accurately determined when the position of the intended drill hole has been selected, by moving the vehicle along the track until the drill steel directly overlies the position of such intended drill hole. The vehicle may be rigidly held in such position by the stop plates U and V which may be brought to bear against the opposite sides of a wheel D and clamped to the rail F by the set screws d.

Upon the completion of the cut, and assuming that it is desired to drill the second hole of the series to the right of the first hole as viewed in Figure 1, the set screw d of the stop plate V is loosened and the plate V moved along the rail F away from the plate U to the extreme limit allowed by the chain X. The plate V is then clamped to the rail F in the new position by the set screw d. Thereafter the vehicle may be moved to a position in which the wheel D will again contact with the plate V and in the new position of the vehicle, the rock drill O will directly overlie the point at which it is desired to drill the next hole. To retain the vehicle in the new position the plate U may be brought up to contact with the opposite side of the wheel D from the plate V and secured to the rail F by its set screw d.

When the broaching of the intervening wall of rock between the holes Q is performed by a rock drill mounted on the frame J and equipped with a suitable broaching tool, the

stop plates U and V may again be employed to determine the position of the vehicle for the several operations.

The position of the vehicle for the first broaching operation may be determined by moving the vehicle along the track until the broaching tool directly overlies the intervening wall of rock between adjacent drill holes which it is desired to break down, and the positions of the vehicle for the subsequent broaching operations may be located in substantially the same manner as described above for locating the position of the vehicle for the drilling operations.

The present invention effects a material reduction in the time required to locate the drilling apparatus for either the drilling or the broaching operations and enables even unskilled operators to accurately space the drill holes. Since the locating device is of simple construction it may be cheaply manufactured and damaged portions thereof replaced at small expense.

I claim:

1. In a locating device for rock drill mountings, the combination with a rock drill mounting which is movable bodily over a rock surface, of a stop plate abutting the mounting for preventing movement of the mounting, means fixed relatively to the rock surface, and means connecting the stop plate and the first said means and adapted to permit the stop plate to be moved a limited distance away from the first said means and the mounting, whereby the mounting may be moved a predetermined distance over the rock surface to again bear against the stop plate.

2. In a locating device for rock drill mountings, the combination of a rock drill mounting which is movable bodily over a rock surface, of a pair of stop plates abutting the mounting to prevent movement of the mounting in the plane of the stop plates, and means connecting the stop plates and adapted to permit one of the stop plates to be moved a limited distance away from the other stop plate, whereby the mounting may be moved a predetermined distance over the rock surface to again abut the moved stop plate.

3. In a locating device for rock drill mountings, the combination of a vehicle having supporting wheels, a rock drill operatively mounted on the vehicle, a track to cooperate with the wheels, stop plates disposed on the track at the opposite sides of one of said wheels, and means connecting the stop plates to determine the spacing of said stop plates with respect to each other, said spacing being of such extent that drill holes drilled by the rock drill with the vehicle in the limiting positions afforded by the stop plates will have a predetermined spacing.

4. In a locating device for rock drill mountings, the combination of a vehicle having supporting wheels, a rock drill oper-

5 atively mounted on the vehicle, a track to cooperate with the wheels, stop plates disposed on the track at the opposite sides of one of said wheels, and flexible means connecting the stop plates to determine the maximum spacing of said stop plates with respect to each other.

10 5. In a locating device for rock drill mountings, the combination with a vehicle supported on wheels and adapted to support a rock drill, and a track to cooperate with said wheels, of a pair of stop plates seated on the track and cooperating with the wheels to prevent movement of the vehicle along the 15 track, and flexible means connecting the stop plates and adapted to permit one of the stop plates to be moved a limited distance along the track away from the other stop plate, whereby the vehicle may be moved a predetermined distance along the track to again 20 abut the moved stop plate.

25 6. In a locating device for rock drill mountings, the combination with a vehicle supported on wheels and adapted to support a rock drill, and a track to cooperate with said wheels, of a pair of stop plates seated on the track and cooperating with the wheels to prevent movement of the vehicle along the track, and flexible means connecting the 30 stop plates and adapted to permit one of the stop plates to be moved a limited distance along the track away from the other stop plate, whereby the vehicle may be moved a predetermined distance along the track to again 35 abut the moved stop plate, said flexible means being adjustable to vary the maximum spacing between the stop plates.

40 7. In a locating device for rock drill mountings, the combination with a vehicle supported on wheels and adapted to support a rock drill, and a track comprising rails to cooperate with the wheels, of a pair of stop plates provided with slots to receive a rail and bearing surfaces to engage the wheels 45 for preventing movement of the vehicle along the rails, and flexible means connecting the stop plates and adapted to permit one of the stop plates to be moved a limited distance along the rail in the direction away from the other stop plate, whereby the mounting 50 may be moved a predetermined distance along the track to again abut the moved stop plate.

55 8. In a locating device for rock drill mountings, the combination with a vehicle supported on wheels and adapted to support a rock drill, and a track comprising rails to cooperate with the wheels, of a pair of stop 60 plates provided with slots to receive a rail and bearing surfaces to engage the wheels for preventing movement of the vehicle along the rails, means to detachably secure the stop plates to the rail, and flexible means connecting the stop plates and adapted to permit 65

one of the stop plates to be moved a limited distance along the rail in the direction away from the other stop plate, whereby the vehicle may be moved a predetermined distance along the track to again abut the moved stop plate. 70

In testimony whereof I have signed this specification.

CHARLES C. HANSEN.
